G. F. RUHL

JOINTED EXTENSIBLE ROD

Filed Aug. 4, 1921

Patented Mar. 20, 1923.

1,449,196

UNITED STATES PATENT OFFICE.

GEORGE F. RUHL, OF TROY, NEW YORK.

JOINTED EXTENSIBLE ROD.

Application filed August 4, 1921. Serial No. 489,811.

To all whom it may concern:

Be it known that I, GEORGE F. RUHL, a citizen of the United States, residing in the city of Troy and State of New York, have invented new and useful Improvements in Jointed Extensible Rods, of which the following is a specification, reference being had to the accompanying drawings.

This invention is in the nature of a jointed extensible rod or pole, and the primary object is to provide a device of this kind in a simple and practicable form, for use in window cleaning, or as a fishing rod, or for any purpose where such an extensible rod would be of an advantage.

In the drawings:

Fig. 1 is a longitudinal sectional view of such a rod as described, the joints thereof being collapsed, or telescoped together.

Fig. 2 is a similar view showing the joints extended.

Figure 3 is a top plan view of the rod, the joints being collapsed.

Fig. 4 is a bottom plan view.

Fig. 5 is a transverse section on the line 4—4 in Figure 3.

The invention lies in providing a number of slotted tubes as 1, 2, 3, of sizes adapted to neatly telescope successively one into the other and each having a slot 7 extended from end to end, but not cut out at the ends. Upon the telescoping ends of each joint are rigidly mounted rings 4, formed with lugs 5 and 6 which extend from the rings down into the slots 7 of the tubes. The lug 6 upon the primary or handle joint 1 is inclined inwardly, while the ring at the end of the joint 3, or end joint, need carry no lug at all as there is no other joint to telescope therewith.

These lugs, sliding along in the slots 7, hold the joints in alignment, and also prevent the joints being pulled entirely apart, as the lugs will impinge the tubes at the ends of the slots 7 as the tubes are drawn out. The lug 6 is inclined inwardly as stated, in order that the twin cams 8 pivoted thereto may be carried entirely inside the tube. The cams 8 serve to lock all the tubes together in collapsed form. The tube 3 is provided at its inner end with a notch 3^a to enable it to straddle the lock 6 and be engaged by the cams 8. For this purpose they are pivoted at 9 one to each side of the lug 6, and a small lock bar 10 has one end pivoted at 11 between the free ends of the cams 8 and ex-

tends back within the handle tube 1, its rear end passing slidably through a stop 12 fixed in the end of the tube 1, while another stop 13 is mounted on the bar 10, spaced from the stop 12. An expanding coil spring 14 is braced between these two stops, and serves to project the bar 10 forwardly, and to lock the cams 8 into contact with the tubes to hold them when shut together. A trigger 15 is fastened at 16 to the bar 10 and projects through a slot 17 in the tube 1. Thus means are afforded for readily manipulating the bar 10. Flat spring hooks 18 extend from under the rings 4 and are adapted to hook into eyes 19 cut in the under sides of the tubes 2 and 3 as means for locking the tubes in extended position. From the above description it is thought the operation of the apparatus is obvious.

While I have herein described a certain specific method of constructing and assembling the elements of my invention, it is understood same may be varied in minor details, not departing from the spirit of my invention as defined in the appended claims.

I claim:

1. An extensible rod, comprising a plurality of longitudinally slotted and telescopically connected tubes; rings over the telescoping ends of the tubes, said rings having lugs slidably engaging the slots of the tubes, so as to hold the joints in alignment; a locking cam pivoted to the lug of the large handle tube; a bar pivoted to the cam and extending back within the tube; means for normally pressing the bar outward against the cam; and means for manipulating the bar within the tube.

2. An extensible rod, comprising a plurality of longitudinally slotted and telescopically connected tubes; rings over the telescoping ends of the tubes, said rings having lugs slidably engaging the slots of the tubes, so as to hold the joints in alignment; a locking cam pivoted to the lug of the large handle tube; a bar pivoted to the cam and extended back within the tube; means for normally pressing the bar outward against the cam; means for manipulating the bar within the tube; and means for releasably locking the joints in extended relation.

GEORGE F. RUHL.
